US0D1046993S

(12) **United States Design Patent** (10) **Patent No.:** **US D1,046,993 S**
(45) **Date of Patent:** **** Oct. 15, 2024**

(54) **FIDGET TOY**

(71) Applicant: **Huizhou Xinaosheng Outdoor Products Technology Co., Ltd.,**
Huizhou (CN)

(72) Inventor: **Jian Huang**, Jiujiang (CN)

(73) Assignee: **HUIZHOU XINAOSHENG OUTDOOR PRODUCTS TECHNOLOGY CO., LTD.**, Huizhou (CN)

(**) Term: **15 Years**

(21) Appl. No.: **29/922,322**

(22) Filed: **Dec. 21, 2023**

(51) LOC (14) Cl. **21-01**

(52) U.S. Cl.

USPC **D21/468**
